UNITED STATES PATENT OFFICE.

JAMES ELMO SMITH, OF URBANA, ILLINOIS.

PROTRACTOR.

977,048.

Specification of Letters Patent. Patented Nov. 29, 1910.

Application filed January 7, 1910. Serial No. 536,930.

To all whom it may concern:

Be it known that I, JAMES ELMO SMITH, a citizen of the United States, and resident of Urbana, county of Champaign, State of Illinois, have invented certain new and useful Improvements in Protractors, of which the following is a specification.

This invention relates to protractors which are adapted for plotting and measuring the directions of lines.

One of the objects of this invention is to construct an instrument by means of which the directions of lines may be plotted and measured by any of the following methods: arcs, trigonometric functions, latitudes and departures, rectangular coördinates, bearings, azimuths.

Another object is to construct an instrument which will combine the functions of the usual triangles, squares and protractors.

Further objects will appear in the detailed description.

The invention will be described in connection with the accompanying drawings, in which—

Figure 1 is a plan view of the instrument; Fig. 2 is a perspective view of the protractor arm and its pivot and clamping means, the parts being separated, and Fig. 3 is a section 30 along the line 3—3 Fig. 1, in which the arm is swung to a position at right angles to the lower edge. Fig. 4 is a plan view showing a logarithmic scale.

The instrument comprises a body or base 35 of rectangular shape forming a base line edge 10 and edges 11, 12 and 13. The base is cut away forming an inner edge 14, which is the arc of a circle, and edges 15 and 16.

A flat over-hanging plate 17 is secured to 40 the base in any suitable manner. In the specific construction shown, this plate is secured by means of screws; it is obvious, however, that the plate may be secured to the base in any other manner, for instance, it may be brazed, soldered or even spot welded thereto. The plate 17 is provided with a bearing aperture 18, for a purpose hereinafter to be described.

An arm 20 has permanently secured to its 50 upper face a threaded bearing ring 21, which is arranged to be journaled in the bearing aperture 18. A clamping ring, or nut, 22 has a threaded engagement with the bearing ring 21 so as to clamp the ring and 55 arm in position on the base. By means of

the above construction the arm 20 is arranged to move in the open space of the base with its lower face in the same plane as the lower face of the base. An extension 23 is arranged to be clamped to the arm by 60 means of screws 24 engaging the threaded holes 25 in the arm. The part 20 and the extension 23 coöperate to form a single arm, and the part 20 is of the same thickness as the base and thus the extension 23 will lie 65 on the upper face of the base of the instrument. The base is cut away at 26 so as to make it as light as possible.

The plate and the base of the instrument are provided with a graduation mark 29, 70 which is opposite the pivotal point 27 and the zero on the edge 11. The arc 14, which is struck from the pivotal center 27 of the arm 20, is graduated in degrees or fractions thereof. The graduations on the edge 14 75 are provided with three rows of reference characters. In the inner row the zero is placed at the upper portion of the scale, the graduations running right and left from 0 to 90. In the second row the reference characters run from 0 to 180, the zero being placed opposite the 90 of the first row. In the third row the reference characters run from 180 to 360, the 180 being placed opposite the zero of the second row. The reference characters in the second and third rows are placed parallel to the edges 12 and 13 respectively, and the reference characters at any point are inversely arranged so that the second row reads normally when the instrument sets on the edge 12, while the third row reads normally when the instrument sets on the edge 13.

The outer edges 11, 12 and 13 are graduated in any suitable units, for instance, in 95 inches or centimeters, and to any suitable scale, the zeros of these graduations being opposite the pivot center 27, so that the pivot center is located at the intersection of lines dropped from the zero points. The 100 graduations extend from zero to 10 at the intersections of the edge 11 with the edges 12 and 13. The edge 15, which is preferably beveled as shown, and which is located on the line between the pivot point 27 and the 105 zeros on the edges 12 and 13, is graduated in the same units as the edges 11, 12 and 13, the zero being at the pivot point 27.

The edge 28 of the arm 20, which is preferably beveled, is graduated in the same 110

units as the edges 11, 12, 13 and 15, the zero being located at the pivot point 27. It will be noted that the edge 28 of the arm is extended beyond the pivot point, and that the portion of the edge within the ring 21 is also graduated. The edge 29 of the extension 23 is graduated in the same units as the edge 28, the extension having the portion corresponding to the graduations of the arm cut away so as to expose the latter when the extension is clamped in position. The distance between the edges 15 and 16 is equal to the width of the arm 20, so that the arm 20 can be moved to position its edge 28 in alignment with the edge 15, so that edges 15, 28 and 29 may form a continuous scale edge.

The operation of the instrument and its use will now be described.

The direction of lines by means of arcs 20 may be readily obtained from the scale on the edge 14. When a trigonometric function of the angle is given, the direction of the line may also be readily laid off, for instance, if the tangent of the angle is given, 25 the arm is moved until the graduated edge 29 coincides with the graduation on one of the edges 11, 12 or 13 corresponding to the natural tangent. The proper scale which must be used will depend upon whether the 30 first, or the second and third rows of figures on the arc are used. In Fig. 1 if the first row is used the angle will be 30° , and it will be seen that the position of the edge 29 on the graduated edge 11 corresponds to the 35 natural tangent of the angle of 30° . Similarly, since the natural secant is the distance between the pivot point 27 and the point where the edge 29 intersects one of the edges 11, 12 or 13 the angle can be readily 40 laid off by swinging the arm until the proper graduation on the edge 29 is in alignment with the proper edge. For angles greater than 45° the co-tangents and natural co-secants can be used; in this way the dimensions of the instrument can be kept down. 45 The position of the arm may also be located if the sine or cosine of the angle is known. This may be accomplished by ruling lines upon the drawing paper, or by laying a 50 straight edge parallel to the edges 11, 12 or 13, and moving the arm until the graduation 55 coincides with the straight edge. The parallel position of the straight edge may be easily obtained by means of the graduations on the edges. The arm can similarly be located if the versed sine or the co-versine are given. The above operations can also be reversed and the functions of angles measured. It will thus be seen that the directions 60 of lines may be plotted and measured on a surface underneath the protractor if the natural trigonometric functions of the angles are given. It is obvious, however, that the edges 11, 12 and 13 may be provided 65 with logarithmic graduations as shown in

Fig. 4 so that the arm may be properly located if the logarithms of the trigonometric functions are given. The body or base of the instrument is cut away so as to leave the interior of the protractor open for plotting 70 and measuring. In this way also the arc 14 can be made large and, therefore, the graduations may be made very fine.

The construction of the open ring 21 enables the draftsman to use the pencil inside of the ring so that the position of the center may be readily determined. The center can also be easily marked by ruling along the edge 28 inside of the ring, and then shifting the arm and ruling another 80 line crossing the first.

The rectangular construction of the frame renders it convenient, since the edges may be used for the same purpose as the edges of the ordinary right angle triangle, the arm 85 28 being used to lay off angles other than right angles.

The rectangular construction of the protractor also makes it convenient to orient. This is of special significance when plotting 90 a traverse line by azimuths or by coördinates where the protractor must be frequently moved and reset. The successive points may be reached by sliding the protractor along a T-square, then along another straight edge 95 at right angles to the T-square until the point is reached. The orientation of the instrument is thus maintained and no time is lost in orienting at each point.

When plotting by latitudes and departures, or by coördinates, the distances may be plotted directly by means of the scales along the edges of the frame. Bearings of lines are plotted by using the inner row of figures along the arc, the zero at the top of the protractor arc representing a point upon a meridian. A line having a bearing of north 30° east, would be plotted by drawing a line from the center toward a point 30° to the right of zero.

The azimuth of a line being its direction as referred to some other line of reference, usually a meridian, the angle made with this reference line is measured clockwise, and continuously from either the north or the south from zero to 360° . For example, a line whose bearing is N. 30° E. has an azimuth of 210° when south is considered as the starting point or zero. The protractor may be graduated to show azimuths either 120 from the north or from the south. In the drawing the azimuths are shown as starting from zero at the south. The outer rows of figures upon the arc are so placed that they cannot be read unless the protractor is set 125 up upon its proper end for reading azimuths, and hence must be read correctly. In addition this arrangement of figures enables one to determine easily and approximately the 130 functions of angles greater than 90° .

By means of the detachable connection between the arm 20 and its extension 23, the protractor may be provided with a number of different sized extensions, so that the protractor may be used for different sized work. A number of arms with different scales may also be used interchangeably. The arm 20, which is wholly inside of the open space, has its lower face located in the same plane as the lower face of the base, and this, together with a beveled construction of the edge 28, enables the directions of lines on a surface underneath the protractor to be accurately plotted and measured. Similarly, the edge 29 engages and contacts with the graduated edges 11, 12, 13 and 14, and thus the angle may be accurately plotted and measured. The clamping ring 22 forms a very convenient clamping device in view of the fact that it is out of the draftsman's way and allows the interior of the bearing ring 21 and the portion of the scale located therein to be clearly visible.

It will thus be seen that this invention provides a very convenient instrument, which combines the functions of the usual triangles and protractor, and also enables the angles to be plotted and measured when their various functions are given. The graduated edges, especially edges 15, 28 and 29, may also be used to serve the purpose of scales. The instrument may be made of any suitable material.

The term "base line" in the claims is to be given its usual meaning, *i. e.*, a reference line. In the instrument the edges 10, 11, 12, 13 and the line 3-3 can be considered base lines. The edges of a T-square, triangle, straight edge, or a line on the drawing board can also be so considered.

It is obvious that various changes may be made in the details of construction without departing from this invention, and it is, therefore, to be understood that this invention is not to be limited to the specific construction shown and described.

Having thus described the invention, what is claimed is:

1. A protractor comprising a base plate 50 rectangular in shape and provided with a plurality of base edges, three edges of said base being provided with trigonometric graduations, and a protractor arm pivoted near the remaining edge at a point equidistant from said graduated edges and cooperating with all of said graduations, a portion of the base between said pivot and graduations being open, and the inside edge of said open space being provided with arc 60 graduations.

2. A protractor comprising a base plate rectangular in shape and provided with a plurality of base edges, the outside edges of said base being provided with equal graduations, the graduations on one of said edges

running in opposite directions from zero at its center to ten at its intersections with the adjacent edges, and the graduations on said adjacent edges running from zero to ten at said intersections, and an arm pivoted on 70 said base at the intersection of lines drawn from said zero points and at right angles to said edges, and coöperating with said graduations.

3. A protractor comprising a base plate 75 rectangular in shape and provided with a plurality of base edges, the outside edges of said base being provided with equal graduations, the graduations on one of said edges running in opposite directions from zero at 80 its center to ten at its intersections with the adjacent edges, and the graduations on said adjacent edges running from zero to ten at said intersections, and an arm pivoted on said base at the intersection of lines drawn from said zero points and at right angles to 85 said edges, and coöperating with said graduations, said arm having equal graduations thereon running from zero at the pivot toward its end, and in the same units as said 90 other graduations.

4. A protractor comprising a base plate 95 rectangular in shape, three edges of said base being provided with graduations, and an arm pivoted near the remaining edge at a point equidistant from said three graduated edges, a portion of the base between said pivot and graduations being open forming 100 an inside edge extending from said pivot toward one of said edges, said edge being provided with graduations, said arm having a graduated edge arranged to be placed in alinement with said inside edge.

5. A protractor comprising a base plate 105 rectangular in shape, three edges of said base being provided with graduations, and an arm pivoted near the remaining edge at a point equidistant from said three graduated edges, a portion of the base between said pivot and graduations being open forming 110 an inside edge extending from said pivot toward one of said edges, said edge being provided with graduations, said arm having a graduated edge arranged to be placed in alinement with said inside edge, all of the 115 graduations on said edges being in the same units, the zero on the outside edges being opposite the said pivot point and the zero on the inside edge and arm being at the pivot point.

6. A protractor comprising a base provided with graduations and having an open space therein, a protractor arm arranged to swing in said space to coöperate with said 125 graduations, and a pivot bearing for said arm comprising an overhanging portion mounted on said base and provided with an aperture, a bearing lug on the upper face of said arm and extending through said aperture and a clamping nut on said lug, where- 130

by the lower face of said arm is arranged to lie in the plane of the lower face of said base.

7. A protractor comprising a base provided with graduations, a swinging arm co-operating with said graduations, and a pivot bearing for said arm comprising an overhanging portion mounted on said base and provided with an aperture and a bearing ring on the upper face of said arm and engaging said aperture, said base being provided with an open portion whereby the lower face of said arm is arranged to lie in the plane of the lower face of said base, and the portion of the edge of the arm in the ring may be visible.

8. A protractor comprising a base provided with graduations, a swinging arm co-operating with said graduations, and a pivot bearing for said arm comprising an overhanging portion mounted on said base and provided with an aperture, a bearing ring on the upper face of said arm and engaging said aperture, and a nut having a threaded engagement with said ring so as to clamp the arm in position, said base being provided with an open portion whereby the lower face of said arm is arranged to lie in the plane of the lower face of said base, and the portion of the edge of the arm in the ring may be visible.

9. A protractor comprising a base provided with graduations, a swinging arm co-operating with said graduations, and a pivot bearing for said arm comprising a flat overhanging plate secured to the upper face of said base and provided with an aperture, and a bearing ring on the upper face of said arm and engaging said aperture, said base being provided with an open portion whereby the lower face of said arm is arranged to lie in the plane of the lower face of said base, and the portion of the edge of the arm in the ring may be visible.

45 10. A protractor comprising a base having an open space therein and provided with

graduations, an arm pivoted to said base so as to move in said space and co-operating with said graduations, said arm and pivot being constructed so that the lower face of 50 said arm lies in the plane of the lower face of said base, and a removable extension clamped to said arm and extending over the upper face of said base.

11. A protractor comprising a base provided with graduations, a graduated arm pivoted on said base, and a removable graduated extension for said arm arranged to be clamped thereto, said extension having the portion corresponding to the graduations on 60 the arm cut away.

12. A protractor comprising a base rectangular in shape and having a graduated arc with its diameter placed parallel to one of the edges of the rectangle, and sets of reference figures on said base running from 0 to 180 and from 180 to 360, the sets beginning at the same point and running in the same direction, the figures at any graduation point being inversely arranged with respect to each other, so that one set reads normally when the base sets on one edge and the other set reads normally when the base sets on the opposite edge.

13. A protractor comprising a base plate 75 rectangular in shape and provided with a plurality of graduated outside edges and with an open space having an inside arc graduated edge, and a protractor arm pivoted on said base near one outside edge and at 80 a point equidistant from the other outside edges and co-operating with all of said graduations, a part of said arm being in said open space with its lower face in the plane of the lower face of said base plate.

In testimony whereof I affix my signature in presence of two witnesses.
